UNITED STATES PATENT OFFICE.

MICHAEL W. MULLEN, OF BALTIMORE, MARYLAND.

MAILING AND DISPLAY PACKAGE.

1,171,231.

Specification of Letters Patent. Patented Feb. 8, 1916.

Application filed June 18, 1915. Serial No. 34,795.

To all whom it may concern:

Be it known that I, MICHAEL W. MULLEN, a citizen of the United States, residing at Baltimore city, State of Maryland, have invented certain new and useful Improvements in Mailing and Display Packages, of which the following is a specification.

This invention is a mailing and display package, and its object is to provide a simple and inexpensive device by means of which advertising and other matter may be sent through the mails without danger of loss, and the package being also so constructed and arranged that the recipient thereof may employ the same for displaying its contents.

The object stated is attained by means of a novel combination and arrangement of parts to be hereinafter described and claimed, and in order that the same may be better understood, reference is had to the accompanying drawing, in which—

Figure 1 is a perspective view of the package folded and ready for mailing; Fig. 2 is a face view of the package unfolded, and in display position, and Fig. 3 is an enlarged vertical section on the line 3—3 of Fig. 2.

In carrying out the invention, there is provided a sheet 5 of pliant material, preferably paper, and of greater length than width. One of the longitudinal edges of the sheet is reinforced by several folds 6, and at the opposite longitudinal edge the sheet has a large continuous fold 7 provided with a reinforced edge formed by a number of folds 8. One of the end edges of the sheet is reinforced by a fold 9.

The fold 7 is designed for the retention of catalogues, booklets, cards or other advertising matter, as well as other mail matter, and said folds are also for the purpose of enabling such matter to be displayed by the recipient thereof. A row of pockets, extending throughout the entire length of the sheet 5, is formed by the fold 7 and by fasteners 10 uniting the same to the main body of the sheet at intervals. The fasteners forming the dividing lines between the pockets are in line with transverse creases 11 in the sheet, and said creases are for the purpose of enabling the sheet and the pockets to be folded as shown in Fig. 1, the creases dividing the sheet into a number of

sections, each of which has a pocket as described.

Along the longitudinal edges of the sheet are eyelets 12 passing through the folded parts. These eyelets are provided in order that the sheet may be hung up when unfolded to display the contents of the pockets. To obtain a better display of the contents of the pockets, the fold 7 has eight openings 13 covered by a sheet of transparent material 14, these openings coinciding with the respective pockets.

As stated, the device is designed for mailing and displaying advertising and other matter, the same being inserted into the pockets as shown in Fig. 2, after which the device is folded on the creases 11, and tied by passing one or more strings 15 around the package formed by the folded sheet, its pockets and the contents of the pockets. Any suitable means 16 may be provided for securing the ends of the tie strings. It will be noted that two adjacent end sections at one end of the sheet are larger than the remaining sections. In folding the device, the small sections are first folded together, and then folded between the two large end sections, so that the latter form, respectively, the front and back of the package. The pockets are thus entirely inclosed and there is no danger of the contents thereof dropping out. The name and address of the person to whom the package is to be mailed is placed on the front of the package as shown in Fig. 1. If the person receiving the package desires to display the contents of the pockets, the package is unfolded flat as shown in Fig. 2, and hung up on a wall or other suitable support by means of the eyelets 12, or by means of hanger cords passing through the eyelets.

The device is simple in construction, it can be easily and cheaply constructed, and it effectually serves the purpose for which it is designed.

I claim:

The combination in a mailing and display package comprising an elongated sheet of pliant material having transverse creases dividing the sheet into a plurality of foldable sections, with two adjacent end sections at one end of the sheet of a greater width than the remaining sections, the latter sec-

2
tions being foldable between said broader end sections, of a fold in the sheet approximately one half its width, at one of its longitudinal edges having a plurality of openings provided therein, fasteners passing through the fold and the body of said sheet to form the folds into a series of pockets,

the openings in the fold forming eight openings in said pockets, and means for securing said foldable sections in folded position. 10

In testimony whereof I affix my signature.

MICHAEL W. MULLEN.
